SUPPORT FOR SPHERICAL CONTAINER

Harry C. Boardman, Chicago, Ill., assignor to
Chicago Bridge & Iron Company, a corporation
of Illinois

Application June 30, 1944, Serial No. 542,993

2 Claims. (Cl. 220—1)

1

This invention relates to a support for a spherical container.

The invention is an improvement on the structure set forth in my Patent 1,953,949, issued April 10, 1934. The invention is especially applicable in connection with spherical containers adapted to contain fluids under pressure, for example, spheres holding compressed gas. Sheet metal spherical gas containers are subject to considerable expansion and contraction due to thermal and pressure variations. Owing to this expansion and contraction of the container, difficulty has been encountered in supporting the same.

In the form of support shown in Patent 1,953,949 a plurality of supports were provided which were unconnected and independent. The upper ends of the supports were attached to the container at points lying substantially in a horizontal plane in which plane the container was subjected to considerable thermal and pressure expansion and contraction, while the lower ends of the supports rested on suitable independent foundations. The unconnected supports themselves had sufficient longitudinal strength to serve as columns in supporting the sphere and sufficient length and transverse flexibility to permit pressure and thermal expansion and contraction in the plane of attachment of the supports.

The present improvement is designed to permit gas holding spheres of the type disclosed in said patent to be tested under hydrostatic pressure while full of water. The present invention also permits the gas holders to be used as water containers if desired. It is primarily intended for strengthening the container to permit hydrostatic testing.

The present invention provides an improved foundation for such supports in the form of a compression ring to which the lower ends of the supports are secured.

In a modified form of the invention the supports are interconnected to form a skirt in the form of a frustum of an inverted cone, the upper edge of which is tangent to the sphere, and the lower end of which rests on the compression ring.

The invention is illustrated in the drawings, in which Fig. 1 is a side elevation of a spherical container supported in accordance with the invention; Figure 2 is a fragmentary detailed sectional elevation of a portion of the structure; Figure 3 is a side elevation of the modified form of the container embodying the frusto-conical support; and Figure 4 is an enlarged fragmentary sectional elevation of a portion of the lower part of Figure 3.

2

As shown in the drawings, 10 indicates a spherical container, for example, one made of a plurality of sheet metal plates welded or otherwise secured together and adapted to contain gas under pressure; 11 indicates a plurality of unconnected and independent supports of the container, the upper ends 11a of which are attached to the container at points lying substantially in a horizontal plane. The lower ends 11b thereof are secured to the compression ring 13 which in turn is mounted on a suitable foundation 14. The supports, as shown in Figure 1, are triangulated by bringing the lower end of one support in each pair adjacent the contiguous member of the next pair and resting the same together on the compression ring. The upper ends of the supports are attached to the container at a point somewhat below the horizontal mid-section thereof, and the lower ends are drawn inwardly so that each support slants outwardly from its lower end to its upper end. As will be noted, the supports thus arranged define the outline of an inverted frustum of a cone and I have found that a structure of that form may be employed as illustrated in Figure 3. As there shown, the spherical container 100 is supported by the inverted frustum of a cone 101, the upper edge 101a of which is tangent to the sphere and is welded thereto along the edge. The lower edge 101b of the frustum is secured to the upper edge of the compression ring 103. In this form of structure, as shown in Figure 4, the triangular space between the frusto-conical skirt 101 and the base 104 of the sphere 100 is hermetically sealed by a continuous radial plate 105 welded to the shell at 106 and to the skirt at 107.

In assembling the structure illustrated in Figures 3 and 4, the skirt is supplied as a unit or single plate, but openings are left therein directly opposite the meridian seams in the shell. The shell is then welded through these seams. After welding, these slots may be permanently closed with bar inserts as indicated at 108 or by plates over the openings. The slots are not, however, essential, but are convenient.

In a container of this type, access is likewise provided by an opening under the foundation to the bottom of the sphere. In this way access may be obtained for welding the radial plate 105 in position. This plate serves to prevent corrosion in the narrow area above the plate where otherwise it would be difficult to paint.

It is understood of course that the principle of support by the skirt is somewhat different from that when the individual supports are uncon-

nected. The skirt, at its point of attachment, acts as a compression ring and restricts the expansion or contraction of the sphere. As a result, bulging or contraction, as the case may be, will occur adjacent the point of attachment of the skirt. The skirt is, however, suitably improved by the use of a compression ring on the foundation, as are the unconnected supports. Furthermore, the point of attachment of the skirt is preferably at substantially the same level as is the case in the unconnected supports.

The foregoing detailed description has been given for clearness of understanding only, and no unnecessary limitations should be understood therefrom.

What I claim as new, and desired to secure by Letters Patent, is:

1. In combination with a spherical container, a plurality of entirely unconnected and independent supports for the same, the upper ends of said supports being attached to the container at points lying substantially in a horizontal plane in which the container is subjected to considerable thermal and pressure expansion and contraction, and a circular compression ring beneath the container having a diameter smaller than

that portion of the container intersected by said horizontal plane, with the lower ends of said supports being attached to said ring, said supports having sufficient longitudinal strength to serve as columns in supporting the container and sufficient length and transverse flexibility to permit said thermal and pressure expansion and contraction.

2. The spherical container of claim 1 wherein the supports are arranged in pairs with the lower ends of each pair adjacent.

HARRY C. BOARDMAN.
